UNITED STATES PATENT OFFICE.

ISIDOR NEWMAN, OF NEW YORK, N. Y.

AUTOMATIC SEAMING MACHINE.

Application filed April 12, 1923. Serial No. 631,590.

To all whom it may concern:

Be it known that I, ISIDOR NEWMAN, a citizen of the United States, and resident of New York city, in the county of New York and State of New York, have invented certain new and useful Improvements in Automatic Seaming Machines, of which the following is a specification.

My invention relates to means for causing tools to automatically advance toward and retreat from articles to be operated upon when such articles are located in the proper position with relation to the tools, and my invention is illustrated in a machine for automatically seaming caps upon metal containers.

In machines for seaming the flanges of caps upon metal containers, such as so-called tin cans, and particularly in such machines comprising rotative rolls or rollers which travel around the margins of the caps to seam the latter to the necks of cans, it has been customary, so far as I am aware, to advance the seaming tools toward the cans or to advance the cans toward the seaming tools while said rolls rotate. In such machines where the seaming rolls or tools have been reciprocated toward the cans in predetermined successive or automatic reciprocations it has been necessary for the operator to be very accurate and expeditious in placing the cans with their caps thereon beneath the seaming tools and in removing the cans with their caps seamed thereon, and in case the cans were not applied and removed in proper timing and sequence there has been danger that the seaming tools would engage the cans or their caps in a wrong position with consequent damage to the cans and liability of injury to the operator.

An object of my invention is to provide means, in the class of machines referred to, to cause advance of the cap seaming tools toward the cans automatically only when a can is placed in proper position beneath the seaming tools; to cause automatic retreat of the seaming tools from the can after seaming, and to prevent further advance of the tools for seaming until a capped can has been removed and a new can placed in capping position. I provide means operated by the can when it is placed in proper capping position upon a support or bed beneath the reciprocative seaming tools to automatically start devices to advance the seaming tools

toward the can and cause said tools to retreat and stop until the capped can has been removed and another can placed in position to have its cap seamed thereon.

My invention is also adapted for use with tools other than for seaming cans, as will be referred to hereinafter.

My invention comprises novel details of improvement that will be more fully herein-after set forth and then pointed out in the claims.

Reference is to be had to the accompanying drawings forming a part hereof, wherein—

Fig. 1 is a side elevation of a machine embodying my invention;

Fig. 1^a is a detail;

Fig. 2 is a view of the machine looking from the left in Fig. 1;

Fig. 3 is a plan view, parts being omitted;

Fig. 4 is an enlarged detail plan view of driving devices;

Fig. 5 is a section on line 5, 5, in Fig. 4;

Fig. 6 is a view partly in section and partly in elevation illustrating tool capping devices;

Fig. 6^a is a detail looking from the right in Fig. 6;

Fig. 7 is a plan view partly in section on the line 7, 7, in Fig. 1;

85

Figs. 8 and 9 are details of clutch devices;

Fig. 10 is a detail section on line 10, 10, in Fig. 7;

Fig. 11 is a section on line 11, 11, in Fig. 10;

90

Fig. 12 is a partly sectional view illustrating modified capping tools;

Fig. 13 is an underside view of Fig. 12;

Figs. 14 and 15 illustrate steps in cap seaming according to the seaming tools of Figs. 1 and 6, and

Figs. 16 and 17 illustrate steps in capping according to the seaming tools of Figs. 12 and 13.

Similar numerals of reference indicate corresponding parts in the several views.

A base or support 1, which may be supported upon a pedestal or in any other suitable way, carries an adjustable head 2 that supports capping devices or seaming tools, indicated generally at 3, located in position above the base or support 1 to operate upon caps α on cans A when in proper position upon said support. The head 2 is preferably adjustable toward and from support 1

110

- to operate respecting cans or articles A of different lengths, for which purpose said head is shown provided with a threaded stem 4 that enters a column 5 on support 1, 5 a suitable hand wheel 6 operative with said stem and column serving to adjust said stem and head 2 vertically, clamping means at 5^a (Fig. 2) serving to retain the stem and head in set position. An arm or bracket 2^a on 10 head 2 is provided with a vertically disposed guiding bearing at 7 in which bearing a tube or sleeve 8 is adapted to slide, which sleeve is provided with a rack 9 exposed through a slot 10 in guide bearing 7, (Figs. 16 1, 6 and 7). A pinion 11 carried by shaft 12 journaled upon head 2 meshes with rack 9 and with a drive gear 13 journaled upon head 2, being secured to a shaft 14. I provide a spring to operate gear 13 to cause 20 rack 9 and its sleeve 8 to rise, which spring may be arranged in any suitable way. In Fig. 7 I have illustrated a spring 15, preferably like a clock spring, shown within a barrel or drum 16 secured on arm 2^a, which 25 spring is attached at one end to drum 16 and at the other end to shaft 12, which the spring surrounds. A sleeve 17 on said shaft is provided with a flange 17^a having spaced holes or notches 17^b. A cover member 18 30 loosely mounted on sleeve 17 fits adjacent to the outer end of barrel 16 and is provided with an internal pin or projection 19 to fit either of the holes or notches 17^b. Cover member 18 has a projection 18^a to engage 35 a stop 16^a on barrel or drum 16, and said member has a screw 20 to engage shaft 12 to retain the member in position, the shaft and sleeve 17 being rotative for adjustment within said member. A pin or bar 21 passes 40 through sleeve 17 and shaft 12 to lock the sleeve to the shaft. The tension of the spring may be regulated by holding shaft 12, withdrawing screw 20, sliding the cover member 18 along the shaft to release pin 19 45 from a notch or hole 17^b of flange 17^a, rotating the cover on the shaft the required amount, entering the pin 19 in a desired notch or hole 17^b, restoring screw 20 against shaft 12, and allowing projection 18^a to engage stop 16^a to retain flange 17^a with spring 15 under the desired tension. The parts described with relation to spring 15 are substantially similar to corresponding parts shown in Letters Patent granted to me 55 October 10, 1922, No. 1,431,749. A handle or rod 22 projects from pin 21 and may be detachably retained by screw 23 (Fig. 7). The handle may be used to rotate shaft 12 manually when it is desired to raise and 60 lower sleeve 8 for any required purpose.
- The sleeve 8 with the tools attached is to be raised and lowered with respect to can or article A by the operation of rack 9 and gears 11, 13. In the example illustrated the seaming tool comprises a body 25 having a head 65 or flange 26 provided with jaws at 27 in which arms 28 are pivoted at 29 and are provided with suitable rollers 30 at their lower ends to engage the flange a' of the can cap a, (Figs. 14-17). The body 25 is slidably attached to a member 31 shown provided with stud screws 32 operative in slots 25^a in member 31 for rotating the latter, (Fig. 6). Member 31 is detachably connected with a tubular spindle or shaft 33 that is rotative in sleeve 8, preferably by means of anti-friction bearings at 34, 34^a, the bearing 34 sustaining spindle 33 on sleeve 8 and the bearing 34^a resisting thrusts on the spindle. The sleeve and spindle are sustained and raised and lowered, by pinion 11. I have shown the lower end of the bore of spindle 33 provided with a tapering seat 33^a receiving a correspondingly tapered portion 31^a of member 31, said member being provided with screw threads at 31^b to engage corresponding threads within the bore of spindle 33, whereby the parts 31 and 33 are secured together for rotation and may be detached. A controlling member is indicated at 35 shown 70 having a cone-like portion 35^a to co-operate with the arms 28, preferably having anti-friction rolls 28^a, which member is preferably adjustably carried by member 31 by means of cooperating threads at 36. The spindle 33, at its reduced portion 33^b above sleeve 8, (Fig. 6), is slidably connected with a gear 37 adapted to rotate said shaft, as by means of a spline and feather between said shaft and gear, through which gear the adjacent portion of the shaft may slide. The gear 37 is in mesh with a pinion 38 on a shaft 39, which may be driven by any suitable means, such as by a belt, gearing or motor. In the construction illustrated the shaft 39 75 is the power shaft of an electric motor B, suitably secured upon head 2, (Fig. 1). A head 40 is secured to a stem 41 as by screw 42, (Fig. 6), which stem is guided in a plug or bushing 43 that is shown adjustably secured in the central bore of body 25 by means of screw threads 44, whereby said plug may be adjusted to be retained in set position by means of screw 43^a. The stem 41 is attached to a rod 45 which is free within and guided by the bores of member 31 and spindle 33, which rod is shown projecting above gear 37. For convenience of connecting rod 45 to head 40 I have shown the lower end of said rod located in a recess 41^a 80 in stem 41 and attached thereto by means of a pin 46, (Fig. 6). Stem 41 has head 41^b adapted to engage plug 43 to limit outward movement of head 40. Anti-friction bearings at 47 are shown provided upon the head 40, adapted to engage the lower end of plug 43, or a washer interposed therebetween, when the parts are in the seaming position. Springs 48 are provided to normally push head 40 away from body 25. Said springs 85 90 95 100 105 110 115 120 125 130

are shown enclosed in tubular members 49 secured to and depending from the body 25, as from its head 26, within which members 49 plugs 50 are slidable and provided with rollers 51 operable upon head 40, the springs 48 serving to normally press said rollers against said head to push the latter and rod 45 outwardly, (Fig. 6). Headed pins at 52 project from body 25 in recesses 53 in arms 28, and springs 54 in said recesses bear against the bottoms thereof and against the heads of pins 52, whereby said arms are normally pressed at their upper ends in the direction of controlling member 35 to normally spread their rolls 30 away from head 40. Rod 45 at its upper end above gear 37 is shown provided with a cross bar or yoke 55 secured thereto by screw 56, and guide rods 57 depend from said bar or yoke and enter guiding bores 58^a in posts or studs 58 secured on arm 2^a on opposite sides of shaft 33 and rod 45, (Figs. 3, 6 and 6^a). Rod 45 thus is slidably supported but prevented from rotating so that head 40 may be retained from rotating when operating in cap *a* of a can A. At such time the spindle or shaft 33, body 25 and parts connected therewith may rotate with respect to the cap to cause the rolls 30 to engage the laterally extending flange *a'* of the cap in cooperation with head 40 that engages the inner flange *a²* of the cap, (Figs. 14 and 16), to seam the flanges of the cap against the neck A' of the can body. The inner flange *a²* of the cap is on the inner side of the neck A' against the neck and the outer flange *a'* of the cap is on the outer side of the neck, whereby the flanges and neck are seamed together, (Figs. 15 and 17). The bar or yoke 55 is adjustable along rod 45 by means of screw 56, and may be secured to said rod in such adjusted position as to engage the posts or studs 58 as a stop to limit the descent of said rod and thereby limit the descent of head 40 against a can cap to prevent undesired pressure of said head against the cap.

When the can A is placed upon support or base 1 in proper seaming position beneath the seaming devices described, the can is stopped against suitable guiding means, indicated at 59 upon said support or base to position the can and its cap properly with respect to the seaming tools. The guiding means 59 is shown in the form of a flanged member, (Fig. 1), adjustable by means of a slot 59^a therein and screw 60 operative in said slot and in support or base 1, to accommodate cans of different diameter. A trip member or lever is indicated at 61, pivotally supported upon column 5 at 62 upon a bracket or arm 63 projecting from the column. Said trip device is shown in the form of a three-armed lever the lower arm 61^a being in position to be engaged by can A' when on support 1 and the upper arm 61^b being cooperative with a rod 63, the arm 61^b and rod 63 being pivotally connected together by means of a pin 64 passing through said rod and arm. Said pin may be retained in place by means of a latch 65 pivoted at 65^a on arm 61^b and provided with a notch 65^b to engage pin 64, (Fig. 1). The arm 61^a is adjustable by means of threads 61^c and retaining nut 61^d, to accommodate cans of different diameter. The upper end of rod 63 is provided with a notch 63^a adapted to receive a pin or projection 66 carried by a rock arm 67. Said arm is shown forked at 67^a to receive and guide the rod 63, (Figs. 3 and 9). The arm 67 is carried by shaft 68 journaled upon brackets or bearings upon head 2, said shaft being provided with an arm or projection 69 to control clutch means to be referred to. When a can is not upon base 1 the trip lever 61 will be substantially in the position shown in dotted lines in Fig. 1, whereupon rod 63 will be in a lowered position and arms 67 and 69 will be depressed. When a can is placed upon support 1 and pushed against the guide 59 the can will cause trip lever 61 to move to the full line position shown in Fig. 1, whereupon arms 67 and 69 will be raised to release the clutch mechanism specified. Rods 63 of different lengths may be interchanged according to the diameter of cans or articles A to be operated on. Means are controlled by rod 63 and arms 67, 69 for operating gear 13 to cause the tools to advance to the can or article A and to release the said gearing for the return of the tools from the can automatically. A sliding bar 70 is mounted in bearings 71, 72 supported by head 2, (Fig. 1), which bar is provided with an arm or projection 73 adapted to operate an arm 74 carried by shaft 14, whereby when bar 70 is moved toward the right in Fig. 1 its arm 73 will operate arm 74 to rotate gear 13 anti-clockwise, whereby pinion 11 will be rotated to cause the descent of spindle 33 and the tools toward the cap on the can A below said tools, and when said bar 70 is released the spring 15 will operate to move said gears reversely to raise spindle 33 and the tools from the can, the arm 74 then operating against arm 73 to return bar 70 to the initial or inoperative position. Arm 74 is preferably provided with an anti-friction roller 74^a to cooperate with arm 73. Arm 74 is shown pivotally attached to shaft 14, preferably being located in a recess 14^a in an enlargement or head 14^b on said shaft, and pivoted by means of a pin 14^c. A spring 14^d cooperating with said head and with a plug 14^e pushes the latter into a recess 74' or 74'' of arm 74 to normally retain arm 74 in set position, (Figs. 1 and 1^a). When it is desired to operate spindle 33 manually the arm 74 may be swung outwardly to be retained by the plug 14^e pressed by spring 14^d into notch 130

74', said plug in notch 74" normally retaining said arm in operative position, (Fig. 1).

A cam 75 secured on shaft 76 cooperates with bar 70 to operate the latter toward the right in Fig. 1 gradually, and when the steep edge 75^a of said cam passes from said rod the latter will be free to be quickly returned by spring 15 to permit relatively rapid rising of spindle 33 and the tools. By preference an anti-friction roll 77 is carried by bar 70 to cooperate with cam 75. Shaft 76 is shown provided with a loose gear 78 in mesh with a gear 79 secured on a shaft 80 journaled in bearings carried by head 2, (Fig. 2), which shaft is shown provided with a worm wheel 81 in mesh with a worm 82 on shaft 39. By means of the gearing described the desired ratio of speed of shaft 76 with respect to the driven shaft 39 is obtained for correspondingly rotating cam 75.

The clutch means before referred to are provided to control intermittent rotations of shaft 76 and cam 75 through the gearing described. A clutch member 83 is mounted loosely on shaft 76 and is secured to gear 78, (Figs. 2 and 4), as by means of screws passing from said gear into threaded holes 84 in clutch member 83, (Fig. 8). A collar 85 secured on shaft 76 adjacent to gear 78 retains the same in operative position, (Fig. 2). The clutch member 83 is shown provided with an extended flange 83^a provided with spaced slots 83^b to be engaged by the end portion 86^a of a dog 86 that is pivotally supported on shaft 76 to rotate therewith, (Figs. 4, 5, 8 and 9). The dog 86 is shown pivotally carried upon a supporting member 87 that is secured to shaft 76, as by a pin 88, (Fig. 9), said member having spaced jaws 87^a supporting pivot or pin 89 upon which the dog 86 is journaled. A spring 90 is secured at one end to member 87 and at the opposite end to dog 86, tending normally to tilt said dog in such a manner as to cause its end portion 86^a to engage a notch 83^b of clutch member 83, (Figs. 5 and 9). The dog is partly enclosed within the flange 83^a, and the portion of the dog outside of said flange is provided with a projection 83^c adapted to be engaged by arm 69, (Fig. 5). When arm 69 is raised from projection 83^c, as in dotted lines in Fig. 5, the spring 90 will cause dog 86 to be tilted to engage its end 86^a in a notch 83^b of clutch member 83, whereby the latter through said dog will cause rotation of shaft 76, and when arm 69 moves into position to engage dog 86 the latter will be tilted to disengage member 83 and stop rotation of shaft 76 and cam 75, although member 83 will continue to rotate.

The operation of arm 69 is controlled by means of arm 67 and rod 63. An eccentric 91 on shaft 76 co-operates with rod

63 to disconnect it from pin 66 of arm 67 when the arm 69 is to oppose dog 86, as in Fig. 5. When eccentric 91 is in position shown in Fig. 1, the notch 63^a of rod 63 will engage pin 66 of arm 67, so that when said rod is raised by the engagement of a can body with lever 61 the arm 69 will be moved from engagement with dog 86 to permit rotation of shaft 76, and during such rotation the eccentric 91 will engage rod 63 and push it to the right in Fig. 1, to release pin 66 and arm 67 from said rod so that the arm 69 may descend into opposition to dog 86 to cause shaft 76 to stop upon making one complete rotation. When the can body is removed from support 1 the rod 63 will descend causing lever 61 to move outwardly and permitting re-engagement of pin 66 with notch 63^a of said rod. Such operations occur each time a can body is placed in position beneath the seaming tools.

I preferably provide braking means to prevent the overrunning of shaft 76 and its cams. I have shown said shaft provided with a brake disk 92 enclosed by a brake band 93 secured at one end to head 2, as by screw 94, (Figs. 7, 10 and 11). The free end of the brake band is shown provided with a screw 95 cooperating with the adjacent portion of the brake band whereby the tension of the band upon the brake drum may be set.

The operation may be described as follows. When the machine is at rest the spindle 33 with its tools will be raised, cams 75 and 91 will be in the position shown in Fig. 1, bar 63 and arms 67, 69 will be in the lower position, and lever 61 will project into the path of can A, as indicated by dotted lines in said figure. When a can A with its cap applied is placed upon support 1 and pushed to proper position beneath the tools, as against guiding stop or stops 59, the lever 61 will be moved to the position shown in full lines in Fig. 1, whereupon rod 63 will be raised to correspondingly raise arms 67 and 69, and dog 86 will be released from arm 69. Spring 90 will cause said dog to engage clutch member 83 and thereupon shaft 76 will be rotated. Cam 75 will push bar 70 to the right in Fig. 1, thereby rotating arm 74 and gear 13, whereby spindle 33 and tools will be advanced to the can, said spindle and tools being continuously rotated by means of gear 37 and the driving devices therefor. During such rotation of shaft 76 the eccentric 91 will tilt rod 63 to the right in Fig. 1 and release arm 67, whereupon said arm and arm 69 will descend, the latter stopping in the path of dog 86. When the high part 75^a of cam 75 passes from bar 70 the spring 15 will rotate gear 13 reversely to cause rising of spindle 33 and the tools

- and the return of bar 70 toward cam 75, the eccentric 91 correspondingly moving away from rod 63 to permit the latter to tilt toward pin 66. When dog 86 encounters arm 69, the dog will release clutch member 83 and shaft 76 will come to rest, having made one complete rotation. The capped can A will be removed from beneath the tools and thereupon rod 63 will descend 10 causing pin 66 again to enter notch 63^a of said rod and causing trip lever 61 to be moved to normal position in the path of a can to be placed upon support 1, the arm 69 remaining opposed to dog 86.
- 15 It will be understood that by the means described the advance of the spindle and tools toward and their retreat from the can A is automatic, and that when the tools have once risen from the can they will not again descend until such can has been removed and another replaced, because arms 67 and 69 remain depressed and arm 69 retains dog 86 out of engagement with clutch member 83, it requiring lever 61 to be pushed back to cause rod 63 to rise to lift arm 69 from dog 86 before the spindle and tools will again advance to the work. Assurance is given the operator that when a can or article of work has once been placed 20 in proper position on support 1 and the tools have operated on the cap upon the can or on such article and retreated that such tools will not again advance until lever 61 has been shifted forth and back, so that 25 there will be no injury to the operator or the can or article, a further assurance being that the tools will not advance until the can or article is in the proper position to have caused the raising of arm 69 from 30 dog 86.
- My improved means for causing the automatic advance and retreat of spindle 33 toward and from the work to be performed may be utilized in connection with any 35 other suitable tool or tools. In Figs. 12 and 13 I have illustrated a modified form of capping tools wherein the arms 28 move directly downwardly toward the flange a' of cap a, the member 35 retaining the arms 40 28 in operating position and being adapted to adjust said arms for different gages of metal of the caps. Instead of the capping tools referred to any other corresponding tools may be used, such as set forth in Letters Patent granted to me, No. 1,266,519, May 14, 1918, and Nos. 1,370,039 and 45 1,370,040, March 1, 1921. Other tools also may be used for other than can capping purposes, such as drills, taps and the like, 50 adapted to be attached to spindle 33 in any ordinary way, such as used in drill presses. When it is desired to cause continuous rotation and reciprocation of spindle 33 and the tool connected therewith the trip member or lever 61 and the rod 63 may be 55 omitted, and the arm or projection 69 may be moved back out of the path of projection 86^c of dog 86, so that said dog will not be actuated, whereby the corresponding clutch devices will remain in engagement 70 and the motor will continuously operate spindle 33.
- Having now described my invention what I claim is:—
1. A machine of the class specified comprising a spindle adapted to support a tool, means including driving means to rotate the spindle, means to reciprocate the spindle, and devices operated by the driving means to actuate said reciprocating means, and means to automatically start and stop said driving means. 75
  2. A machine as specified in claim 1, in which said reciprocating means includes a cam. 80
  3. A machine of the class specified comprising a spindle adapted to support a tool, means including driving means to rotate the spindle, means to reciprocate the spindle including clutch devices and means operated by the driving means to actuate the clutch devices. 90
  4. A machine as specified in claim 3, comprising a cam operated by the clutch devices to actuate the means to reciprocate the spindle. 95
  5. A machine of the class specified comprising a spindle adapted to support a tool, means to rotate the spindle, means to reciprocate the spindle, including clutch devices 100 and an arm to start and stop said last named means, a rod to actuate said arm, a movable member connected with the arm and normally in position to be engaged by an article in operative relation to the spindle, and means controlled by said spindle reciprocating means to release the rod from said arm. 105
  6. A machine of the class specified comprising a spindle adapted to support a tool, means to rotate the spindle, means to reciprocate the spindle including clutch devices 110 and an arm to start and stop said means, a rod to actuate said arm, a movable member connected with the arm and normally in position to be engaged by an article in operative relation to the spindle, and a cam operative with said spindle reciprocating means to release said rod from said arm for positioning the latter with relation to the 115 clutch devices. 120
  7. A machine of the class specified comprising a spindle adapted to support a tool, means to rotate the spindle, means to reciprocate the spindle including clutch devices 125 and an arm to start and stop said means, a rod to actuate said arm, a lever pivotally connected with said rod and having a member normally in position to be engaged by an article when in operative position re- 130

specting the spindle, and means operative with said spindle reciprocating devices to release said rod from said arm during reciprocations of the spindle.

5 8. A machine of the class specified comprising a spindle adapted to support a tool, means to rotate the spindle, means to reciprocate the spindle including clutch devices and an arm to start and stop said 10 means, a rod to actuate said arm, a lever pivotally connected with said rod and having a member normally in position to be engaged by an article when in operative position respecting the spindle, and a cam to 15 operate said rod to release it from said arm to cause the arm to position itself respecting the clutch devices.

9. A machine of the class specified comprising a spindle adapted to support a tool, 20 means to rotate the spindle, gearing to reciprocate the spindle, means to rotate the gearing in opposite directions including a cam and clutch devices to rotate the cam intermittently, an arm to control the clutch 25 devices, a rod to actuate the arm, means to release the rod from the arm, and a member connected with said rod and normally in the path of an article to be placed in operative position respecting the spindle to actuate the rod and arm to release the clutch 30 devices.

10. A machine of the class specified comprising a spindle adapted to support a tool, means to rotate the spindle, gearing to reciprocate the spindle, means to rotate the gearing in opposite directions including a cam and a clutch device to rotate the cam intermittently, an arm to control the clutch 35 devices, a rod to actuate the arm, a lever pivotally connected to said rod and having a member normally in the path of an article to be placed in operative relation to the spindle for actuating the rod, and means to actuate the rod to cause release of the clutch 40 devices.

45 11. A machine of the class specified comprising a spindle adapted to support a tool, means to rotate the spindle, gearing to reciprocate the spindle, means to rotate the gearing in opposite directions including a cam and clutch devices to rotate the cam intermittently, an arm to control the clutch devices, a projection connected with said arm, a rod having a notch to receive said 50 projection, means operative by said clutch devices to release the rod from the projection, and a movable member operatively connected with said rod and having a portion normally in position to be engaged by an article placed in operative relation to the spindle for causing the rod to move the arm to release the clutch devices.

60 12. A machine of the class specified comprising a spindle adapted to support a tool, means to rotate the spindle, gearing to reciprocate the 65

ciprocate the spindle, means to rotate said gearing in opposite directions including a cam, and means to actuate the cam.

13. A machine as specified in claim 12 in which the means to actuate the cam includes clutch devices. 70

14. A machine of the class specified, comprising a spindle adapted to support a tool, gearing to rotate the spindle, a drive shaft for the gearing, gearing to reciprocate the 75 spindle, and means operative by said shaft to actuate said gearing.

15. A machine as specified in claim 14 in which the means to actuate the second named gearing includes a cam. 80

16. A machine of the class specified, comprising a reciprocative spindle, means to rotate the spindle, gearing to reciprocate the spindle, a bar cooperative with the gearing to rotate it in one direction, a spring 85 cooperative with the gearing to rotate it in the opposite direction, a cam to actuate the bar, and means to actuate the cam.

17. A machine as specified in claim 16 in which the last named means includes 90 clutch devices.

18. The combination of a spindle, means to rotate the spindle, a body movable along the spindle, means to rotate the body by the spindle, a rod slidable in the spindle and 95 body, a head connected to the rod to engage a can cap, arms carried by the body and provided with rollers to engage a flange of the cap, means cooperative with the arms to cause the rollers to act on said flange, and means to reciprocate said spindle, body and rod relatively to said can and cap. 100

19. A machine as set forth in claim 18 including means to resist rotation of said rod. 105

20. The combination of a spindle, means to rotate the spindle, a body movable along the spindle, means to rotate the body by the spindle, a rod slidable in the spindle and body, a head connected to the rod to engage a can cap, arms carried by the body and provided with rollers to engage a flange of the cap, means cooperative with the arms to cause the rollers to act on said flange, means to reciprocate said spindle, body and rod relatively to said can and cap, means to resist rotation of said rod including a guide rod carried by the first named rod, and a member having a bore slidably receiving the guide rod. 110 115

21. The combination of a hollow spindle, means to rotate the spindle, a hollow body, a member slidably connected with said body and having a bore, means to rotate the body by said member, means to rotate the member by the spindle, a rod within the bores of the body, member and spindle, a head attached to the rod below the body to engage a can cap, arms pivotally carried by the body and provided with rollers to 120 125 130

- cooperate with a flange of the can cap to seam it to the can neck, means to resist movement of the head during the capping operation, means to retain the arms in capping position, and means to reciprocate said spindle, body, member and rod.
22. A machine as specified in claim 21, including means to resist rotation of said rod and permit it to reciprocate.
- 10 23. The combination of a hollow spindle, means to rotate the spindle, a hollow body, a member slidably connected with said body and having a bore, means to rotate the body by said member, means to rotate the member by the spindle, a rod within the bores of the body, member and spindle, a head attached to the rod below the body to engage a can cap, arms pivotally carried by the body and provided with rollers to operate with a flange of the can cap to seam it to the can neck, means to resist movement of the head during the capping operation, means to retain the arms in capping position, means to reciprocate said spindle, body, member and rod, and means to resist rotation of said rod and permit it to reciprocate including a bar attached to the rod, a guide rod depending from the bar, and a member having a bore receiving the guide rod.
- 15 24. A machine of the class specified comprising a hollow sleeve, means to reciprocate the sleeve, a hollow spindle journaled in the sleeve, a member having a bore secured to the spindle, a hollow body slidably connected with said member, means to rotate the body by the member, a rod in said body, member and spindle, a head connected with the rod, and rollers carried by the body to cooperate with the flange of a cap engaged by said head to seam the cap on a can neck.
- 20 25. A machine as specified in claim 24, including means to prevent rotation of said rod and permit reciprocation thereof with the spindle and sleeve.
- 25 26. The combination of a spindle, means to rotate the spindle, a body movable along the spindle, means to rotate the body by the spindle, a rod slideable in the spindle and body, a head connected to the rod to engage a can cap, arms carried by the body and provided with rollers to engage a flange of the cap, means cooperative with the arms to cause the rollers to act on said flange, means to reciprocate said spindle, body and rod relatively to said can and cap, a bar connected to said rod, and a stop to engage the bar to limit advance of said head toward the can.
- 30 27. A machine as set forth in claim 29 provided with means to retain said bar in adjusted position along the rod.
